United States Patent Office

Des. 219,622
Patented Dec. 29, 1970

219,622

PORTRABLE RADIO

Richard Culbertson, Manlius, N.Y., assignor to General
Electric Company, a corporation of New York

Filed Dec. 10, 1969, Ser. No. 20,429

Term of patent 14 years

Int. Cl. D14—03

U.S. Cl. D56—4

FIG.1

FIG.2

FIG.3

FIG.4

FIG.5

FIG.6

FIG. 1 is a front, top and right side perspective view of a portable radio in accordance with my design;

FIG. 2 is a front elevational view;

FIG. 3 is a right side elevational view;

FIG. 4 is a left side elevational view;

FIG. 5 is a rear elevational view; and

FIG. 6 is a top plan view thereof, the bottom being substantially a mirror image thereof.

I claim:

The ornamental design for a portable radio, as shown and described.
